UNITED STATES PATENT OFFICE.

WALTER H. SMITH, OF PITTSBURGH, PENNSYLVANIA, ASSIGNOR TO MILLER SAW-TRIMMER COMPANY, OF PITTSBURGH, PENNSYLVANIA, A CORPORATION OF PENNSYLVANIA.

PRINTING PRESS.

Application filed July 17, 1922. Serial No. 575,517.

To all whom it may concern:

Be it known that I, WALTER H. SMITH, a subject of the King of Great Britain, residing at Pittsburgh, in the county of Allegheny and State of Pennsylvania, have invented new and useful Improvements in Printing Presses, of which the following is a specification.

My invention pertains to cylinder printing presses, and has as its principal object the provision of a printing press in which a high degree of accuracy may be obtained in the rolling contact between the impression member and the printing member, without exceptional cost of manufacture.

I have described in the following specification, and shown in the accompanying drawings, my invention as employed in connection with a printing press of the type disclosed in Letters Patent of the United States No. 1,167,666 granted January 11, 1916 on the application of Swan Smith and Oscar W. Hammerquist.

In the drawings:

Fig. 1 is a view in vertical section of a press of the type disclosed in the said patent issued to Smith and Hammerquist;

Fig. 2 is a side elevation of the same, showing the parts in a different position;

Fig. 3 is an end view, looking from the left-hand side of Fig. 2; and

Fig. 4 is a detail of a gear wheel carried by the press cylinder.

A press of the type described in the said Smith and Hammerquist patent comprises a frame 10 provided at its upper part with slideways 11 in which are mounted reciprocating blocks 12. The cylinder 13 is journaled in these blocks, and has a reciprocating movement imparted to it, as well as a continuous rotating movement in one direction. The press frame also has mounted therein, so as to be capable of a vertical reciprocating movement, supporting slides 14, on which reciprocates the type bed 15. As the bed 15 moves towards the left, the cylinder moves over it to the right (Fig. 1), thus performing the printing operation. Prior to the return movement of the bed, the supporting slides 14 are lowered, whereby the bed makes its return movement on a lower plane, out of contact with the cylinder 13 as the latter returns in the opposite direction. The construction is such that the bed and

cylinder have a dwell at each end of their reciprocating movement. During the dwell at one end the sheet is fed to the cylinder, and during the dwell at the other end the sheet is delivered from the cylinder.

The reciprocation of the cylinder 13 is effected by means of a cam segment 16 secured to a rock shaft 17 and actuated by a double-faced cam 19, each face of the said cam 19 operating upon a cam roller 20 carried by the segment 16. The rock shaft 17 is connected by levers 21 and connecting rods 22 with the reciprocable blocks 12 in which the cylinder has its bearings. As will be seen, the faces of the cam 19 are so formed as to cause the reciprocation of the cylinder, and provide the dwell, above referred to, at each end of the stroke.

The reciprocation of the type bed 15 also is effected by the segment 16, which carries an arm 23 linked to a bell-crank lever 24, which, in turn, is connected to the bed 15 by means of an adjustable connecting rod 25. The raising and lowering of the bed-supporting slides 14 is effected by an internal cam 26 which actuates one of a pair of pivoted levers 27, the free ends of which are normally connected by a bar 28. One of these levers is connected with a pair of eccentric arms 29 operating eccentrics 30. The eccentrics 30 serve to raise or lower a pair of vertically movable beams 31, one on each side of the press, which beams carry standards 32 on which the bed-supporting slide 14 is mounted. By means of a pedal 33 the mechanism for actuating the supporting slide 14 may be thrown out of operation, so that the slide will not be raised during that particular cycle of the press, this being done for the usual "throw-out" purposes.

The press receives its power from a driven pulley 34, having thereon a pinion which meshes with a gear 35 mounted on the press shaft 36. Meshing with the gear 35 is an idler gear 36^a, of the same diameter, which in turn meshes with a gear wheel 37 carried by the cylinder shaft 38. The idler gear 36^a is supported by links 39 and 40 extending respectively from the cylinder shaft 38 and the press shaft 36.

It will be seen from the above that the cylinder rotates at all times in the same direction. As it moves to the right, for printing, it has a geared relation, by means

of a partial gear wheel 41 which it carries, with a register rack 42 carried by the bed 15. This rack 42 is long enough so that it will engage the partial gear 41 somewhat before the bed comes into actual printing relation with the cylinder, and for a short time after the bed has passed out of actual printing relation with the cylinder. This lap at each end ensures a smooth engagement of rack and gear during the printing operation. The rack 42 and partial gear 41 do not engage, of course when the bed is in its lowered position. During its dwell, and subsequently when it moves to the left after the printing operation, the cylinder still continues to rotate in the same direction as before.

Since both the cylinder 13 and the bed 15, with their interengaging gear 41 and rack 42, are definitely driven by the above-described series of mechanical parts, and since the cylinder is additionally definitely rotated by the train of gears 35, 36^a and 37, it is evident that a minute accuracy, obtainable only at considerable expense, must be followed in the manufacture of these parts, particularly the double-faced cam 19, in order that the required highly accurate rolling contact may be obtained.

According to my invention, I relieve the driving faces of those of the teeth of the gear wheel 37 which will be in mesh with the idler gear 36^a at the same time as the gear 41 is in engagement with the register rack 42. In the construction shown, this will be about one-half of the teeth of the gear wheel 37. As indicated in Fig. 4, this relieving of the teeth is gradual for the first few and last few of the series of teeth relieved. In Fig. 4, the partially relieved teeth are indicated at *b* and the fully relieved teeth at *c*. The partially relieved teeth *b* will engage the idler gear 36^a at the time when the laps of the rack, one at each end of the part which is operative during actual printing engagement of bed and cylinder, are meshing with the partial gear 41. When the main part of the rack 42 is in engagement with the partial gear 41, i. e., during the actual printing portion of the cycle, the fully relieved teeth *c* of the gear wheel 37 will be meshing with the idler gear 36^a, although not driven by the latter. In short, the faces of the teeth of the gear wheel 37 are relieved in such a manner that the partial gear 41 will be accurately and smoothly brought into engagement with the register rack 42, and will thereafter be driven by such rack alone, without any driving effect from the gear wheel 37. Any driving

effect from the gear wheel 37 is obviated, during this period, by reason of the clearance which exists between its relieved teeth and the teeth of the idler gear 36^a.

The operation of the press described above, as constructed in accordance with my invention, is therefore, as follows:

With the parts in the position shown in Fig. 1, assuming that the cylinder has just begun its movement to the right and its partial gear 41 has just come into mesh with the extending end, or lap, of the register rack 42, the first of the gradually relieved teeth *b* will have passed into mesh with the idler gear 36^a, and the first of the fully relieved teeth *c* will be just about to mesh with said idler gear, as the printing part of the cycle commences. Owing to the relieving of these teeth the gear wheel 37 will not have any driving effect upon the cylinder, the rotation of the cylinder, at this time, being effected solely by the engagement of the register rack 42 with the partial gear 41. Thus a highly accurate rolling contact of bed and cylinder, during the printing portion of the cycle, is obtained. During the dwell periods, full-size teeth of the gear wheel 37 are engaged by the idler gear 36^a. During the return reciprocation of the cylinder, the engagement of the teeth of the idler gear 36^a with the relieved teeth of the gear wheel 37 is sufficient to rotate the cylinder, as also is the case during the forward reciprocation of the cylinder at those times when the bed is thrown out of operative relation with the cylinder by the use of the pedal 33, or otherwise.

Having thus fully described my said invention, what I claim as new, and desire to secure by Letters Patent, is:

In a printing press, a cylinder member; a bed-member; means for moving one of said members laterally with respect to the other, to effect the printing operation; means for moving one of said members transversely with respect to the other to separate said members during a portion of the cycle; a gearing connection between said members operative only when said members are in a non-separated condition, whereby said cylinder member is rotated when in such non-separated condition; and separate gearing for rotating said cylinder, said last-named gearing having a series of its teeth relieved to a progressive extent so as to be operative when said gearing connection is inoperative, but not operative coincidently with said gearing connection.

WALTER H. SMITH,
